UNITED STATES PATENT OFFICE.

CLAUDE S. LONG, OF RALEIGH, NORTH CAROLINA, ASSIGNOR OF ONE-HALF TO
CHARLES F. KOONCE, OF RALEIGH, NORTH CAROLINA.

SLUG ADJUSTER.

Application filed March 7, 1923. Serial No. 623,519.

To all whom it may concern:

Be it known that I, CLAUDE S. LONG, a citizen of the United States, residing at Raleigh, in the county of Wake and State of North Carolina, have invented new and useful Improvements in Slug Adjusters, of which the following is a specification.

This invention relates to improvements in type setting machines and has more particular relation to a slug adjuster for linotype machines.

An object of the present invention is the provision of a slug adjuster which may be easily attached to a machine and which will effectually act to trip and direct a slug into the machine galley.

Another object of the invention is the provision of a device of this character which may be adjusted to slugs of different lengths and which will yield to permit of the simultaneous passage of more than one slug, without damage to the adjuster.

With the above and other objects in view, the invention further includes the following novel features and details of construction, to be hereinafter more fully described, illustrated in the accompanying drawings and pointed out in the appended claims.

In the drawings:-

Figure 1 is a fragmentary perspective view showing a portion of a linotype machine with the invention applied.

Figure 2 is an edge view of the adjuster removed from the machine.

Figure 3 is a fragmentary perspective view of the upper end of the U-shaped guide member.

Referring in detail to the drawings, like characters of reference denote corresponding parts throughout the several views.

In illustrating the invention there is shown a portion of a linotype machine, the slug channel being indicated at 10, the galley supporting bracket at 11, the galley at 12 and the vise at 13, while a portion of the frame of the machine is shown at 14. The adjuster comprises an inverted substantially U-shaped member which includes spaced parallel arms 15, connected by a transverse arm 16. The transverse arm 16 is hingedly secured to one end of an attaching plate 17, as shown at 18, while the plate 17 is attached to the vise 13 of the machine by means of a screw 19.

The transverse arm 16 has extending

therefrom an offset portion 20 and this portion is engaged by a spring finger 21 which extends from the plate 17, the action of this finger being to yieldingly force the arms 15 of the U-shaped member inward.

The U-shaped member provides a guide for a roller 22, the latter being positioned transversely between the arms 15 and having its opposite ends supported by bearing sleeves 23 which are slidable upon and frictionally engage the arms 15 of the guide member.

The adjuster will thus be positioned over the slug channel 10 and the slug in its passage through this channel to the galley 12 will be engaged and tripped by the roller 22 so as to be properly positioned within the galley. The roller may be adjusted longitudinally of the arms 15 so as to be positioned for proper contact with a passing slug, the adjustment of the roller depending upon the length of the slug. In the event of more than one slug inadvertently passing through the slug channel, the adjuster will be moved outward against the action of the spring finger 21 without damage and will return to proper position after the slugs have passed.

The invention is susceptible of various changes in its form, proportions and minor details of construction and the right is herein reserved to make such changes as properly fall within the scope of the appended claims.

Having described the invention what is claimed is:-

1. In a slug adjuster, the combination with a type setting machine, of an inverted substantially U-shaped guide member including spaced parallel arms and a transverse connecting arm, means for pivotally securing the said member in position over the slug channel of the machine, means included in the pivotal securing means for yieldingly holding the guide member in position and means carried by the guide member in the path of the slug for tripping the latter to properly position said slug within the machine galley.

2. In a slug adjuster, the combination with a type setting machine, of an inverted substantially U-shaped guide member including spaced parallel arms and a transverse connecting arm, a plate having one end hingedly secured to the guide member

and its opposite end secured to the machine for holding said member in position over the slug channel, an offset portion extending from the transverse connecting arm of the

5 U-shaped member, a spring finger carried by the plate and engaging the offset portion to yieldingly hold the guide member in

position and means carried by the guide member in the path of the slug for tripping the latter to properly position said 10 slug within the machine galleys.

In testimony whereof I affix my signature.

CLAUDE S. LONG.
